TWIN HEAD TOOTHBRUSH AND CUSTOM COVERS

Ira Danchig, New York, N. Y., assignor of fifty per cent to Peter Fries, Jr., New York, N. Y.

Application December 16, 1950, Serial No. 201,117

1 Claim. (Cl. 15—184)

This invention relates to improvements in devices for cleaning and brushing.

An object of the invention is to provide a novel and improved device for cleaning and brushing, in which a plurality of cleaning and brushing elements are cooperatively integrated for unitary results.

Another object of the invention is to provide a novel and improved device for cleaning and brushing portions of the body, including the teeth, a plurality of operative heads being provided in mutually integrated disposition, and in which novel means are provided for safeguarding and protecting each of said operative heads against damage or deformation.

A further object of the invention is to provide a novel and improved device incorporating a plurality of cleaning and brushing operative elements mutually integrated, for selective or joint use, and including a plurality of protective removable covering means arranged for removable engagement therewith so as to provide protection for the bristle elements thereof, the mode of engagement and disengagement being quite simple and novel, and secure.

Still another object of the invention is to provide a novel composite toothbrushing device in which dual covering elements are provided for each brushing head, and wherein, upon uncovering of one such brushing head for employment in cleaning and brushing operations, the remaining covering element coats with the remaining covered device body and brushing head to form a handle and grip for securely holding the device while in use, and for protecting at the same time, the brushing head from contamination and deformation.

Still a further object of the invention is to provide a novel composite toothbrushing device in which novel covering elements are provided for each brushing head, the covering elements being constructed and arranged so as to provide protection for the brushing elements against contamination, deformation and damage, and at the same time providing air circulation means so that free access to the bristles is provided at all times, with its drying and germicidal properties.

Another object of the invention is to provide a novel brush head covering device of the character described, which may be employed with other toothbrushing devices.

Still another object of the invention is to provide a novel brushing and cleaning device of the character described, which is simple in design, inexpensive to manufacture, and which is highly effective and efficient for its intended purposes.

These and other objects and advantages of the invention will become apparent from the following description of a preferred embodiment thereof as illustrated in the accompanying drawings forming a part hereof, and in which,

Figure 1 is a top plan view of my novel and improved device shown in Figure 2, both covering members being in positions completely closing the device.

2

Figure 2 is a longitudinal sectional elevational view taken on plane 2—2 of Figure 1.

Figure 3 is a left end elevational view as seen on plane 3—3 of Figure 2.

5 Figure 4 is a transverse sectional elevational view taken on plane 4—4 of Figure 2.

Figure 5 is a fragmentary front elevational view of the right hand covering member shown in Figures 1 and 2, omitting the brush head, the view being broken out.

10 Figure 6 is an assembled view similar to that of Figure 2, one covering member being shown in closed position, while the other covering member is shown in partly opened position and broken out.

Figure 7 is a perspective view showing the completely 15 assembled and closed device in hanging position upon a bathroom fixture.

In the use of brushing and cleaning devices, it is most 20 important that they be maintained in a sanitary condition. Such considerations are essential especially when

25 such devices are employed for cleaning the teeth and mouth. They should be protected from contact of their working surfaces and bristles with any contaminating influence, but the covering means should not prevent adequate contact with surrounding air, so that it may both dry and protect their surfaces and bristles.

In traveling, it is often quite inconvenient to take 30 along more than one toothbrush, even when two persons are traveling together, and it is an advantage of the present invention that two persons may employ the same unitary tooth brushing and cleaning device, without in any way detracting from the sanitation or convenience thereof. Further, where one person alone, employs the device, as a result of its dual brushing head construction and the novel protective and covering means, a longer 35 drying period is permitted for each brushing element, so that its bristles remain firmer and do not deteriorate into a soggy mass, their life being considerably prolonged over devices not having these advantages.

In order to understand clearly the nature of the 40 invention, and the best means for carrying it out, reference may now be had to the drawings, in which like numerals denote similar parts throughout the several views.

As shown, there is a brush body 10 formed into two 45 brush body halves 12 and 14 extending in opposite directions out of the central hub 20 and integrated therewith. Secured to the outer end portions of the body halves 12 and 14 respectively, are the brush head extensions 16 and 18, and these heads have bristles 24 and 22 respectively, seated in sockets 26 formed in their under-surfaces. The bristles are set in a series of groups, and 50 may be in one or more longitudinal rows, as seen best in Figure 4. It is seen that the brush head extensions 16 and 18 terminate in rounded end portions 32 and 30 respectively. The hub 20 is thus disposed midway between the two ends 30 and 32, as shown at location 34, and the intersection of the hub with the two halves 12 and 14 may preferably be smoothly rounded as shown at 55 34 to block accumulation of debris and to facilitate cleaning.

60 Covering members 36 and 38 are provided as shown, these being so arranged as to cover and protect the brush heads with their bristles, from contamination and to keep them clean. As seen best in Figure 1, the broad top surfaces of the members 12 and 14 may be made

65 slightly narrower in width than that of the members 16 and 18 respectively, the areas of merger being smoothly tapered as shown.

The covering members 36 and 38 each have side walls 40 and 42 which are spaced as seen best in Figure 4, and 70 interconnected at the top and bottom by top and bottom walls 46 and 44 respectively, with end walls 50 defining chambers into which the brush heads may be received.

slidably as in the manner shown best in Figures 2 and 6. When in closed positions, the inner open ends of the covering and handle members 36 and 38 are brought into contact abutment with the hub shoulder 20 as seen best in Figures 1 and 2. The end walls 50 are provided with air circulation and venting openings 52, the bottom walls 44 are provided with openings 54, and similarly the top walls 46 are provided with openings 56. In this manner, when the bristles are totally enclosed by the covering and handle members 36 and 38, as seen in Figures 1 and 2, there is cross ventilation between these holes, 52, 54 and 56, all around the brush heads, bristles, and body halves 12 and 14, and around the ends 30 and 32, which as seen, are spaced from the end walls 50 of the covering members, preferably.

Elongated ribs 66 are formed integral with the left and right sides of the brush head extensions 16 and 18, as seen best in Figure 4, and also in Figure 2, substantially of the longitudinal extent shown, although this may be varied to be equal to the entire length of the brush head extension 16 or 18. There is a corresponding groove 68 formed in the inner surfaces of the walls 40 and 42 of the housings 36 and 38, to receive these ribs 66 when the housings are engaged with the brush heads, allowing slidable engagement of the ribs with the grooves as the housings are either moved toward the hub 20, or away therefrom for disengagement. The grooves 68 may be either the entire length of the covering housings 36 or 38, that is from left to right as seen in Figures 1 and 2, or may be somewhat shorter, as shown in Figure 5, in which latter event, the thickness of the wall to the left of the slot 68 would be reduced on its inner surface somewhat, to allow the ribs 66 to reach and enter the grooves 68. Where the material forming the covering housings 36 and 38 is plastic, and somewhat resilient, it may be found that sufficient "give" exists to permit the ribs 66 to move past and into the grooves 68 so as to effect snap engagement therewith. In any event, there will be frictional engagement of the ribs with their respective grooves 68, sufficient to hold the parts in mutual engagement as shown in Figure 1, without accidental disengagement. Further it will be understood that where the parts 14 and 12 are of the same width as the brush heads 16 and 18 as seen in Figure 1 rather than narrower as actually illustrated, then the ribs 66 could be, though they need not, the added length of the portions 12 and 14, in which event the grooves 68 would be lengthened to accommodate them.

It is seen that the grooves 68 and ribs 66 are smoothly rounded off as shown, so as to avoid any damage to the sensitive gums, teeth and mouth tissues of the user, and to make for a high degree of sanitation and ease of cleaning the same.

Hook members 64 have legs 58 secured to or integrated with the walls of the covering housings 36 and/or 38, and have webs 60 connecting the legs 58 with the outer legs 62 which are thus spaced from the walls 44. These hook members allow the engagement with any suitable support, such as the bathroom fixture shown at 65 in Figure 7, which has openings 67 normally placed there to receive the shanks of toothbrushes of conventional prior art forms, with single brush heads, in which prior art cases their brush bristles are in contact with the surface of the fixture 65. As seen in Figure 7, several such toothbrush devices as disclosed herein, may be hung from the fixture 65, one for each opening 67, and, since my device has two brush heads in each device, the number of useful brush heads hung from the fixture 65 is doubled without crowding.

As seen best in Figures 1, 2, 3 and 4, the novel arrangement permits the entire or substantially entire brush heads and bristles to be out of contact with the surrounding inner walls of the covering housings 36 and 38, thus avoiding distortion of the bristles, and maintaining the

bristles in sanitary condition as well as keeping the other surfaces also quite clean. Further, a constant circulation of air is permitted across and throughout the interior of the brush covering members 36 and 38, allowing the parts and bristles to dry and remain germ free, avoiding moisture. It is also seen that when, as seen best in Figure 6, one of the brush heads is to be used, it is only necessary to grasp the right hand covering case 38 and the hub 20 with the right hand, and with the left hand to pull the left hand covering case 36 toward the left and entirely off the left hand brush head, which may then be used, the right hand covering case 38 serving as a sturdy handle, and making sure that there is no contact of the hand with the right hand brush head at all. The same procedure applies when the right hand brush is to be used, in which event the left hand is used to hold the left hand housing 36 and the hub 20, while the right hand pulls the right hand housing 38 to the right, and out of engagement so that the right hand brush can be used, the left hand housing 36 then serving as the handle. It will also be noted that one of the fingers of the hand may be engaged with the hook 64 of its respective handle 36 or 38, so as to make for added firmness of grip of the device when used, this being especially important when the hands may be soapy and not able to grasp objects readily without dropping them.

Two persons may also make use of the same composite device shown in Figure 1, each person using his own brush head portion at a time, and neither contaminating the other's brush. This makes it easy to carry it in the pocket or traveling bag, making it quite compact. Further, one person may use the device, by, if he chooses, using one brush head in the morning and the other at night, allowing them to dry thoroughly and hence have a longer life. Children can be taught to do this, brushing their teeth twice a day, once with each brush head.

Although I have described my invention in specific terms, it will be understood that various changes may be made in size, shape, materials and arrangement without departing from the spirit and scope of the invention.

I claim:

A cleaning device comprising a lateral wall forming a hub means, first and second body shanks secured to and extending in opposite directions out of said hub means, brush heads secured to said first and second body shanks, brushing and cleaning bristles on said brush heads, first and second hollow covering and handle means open at one end for engaging and normally covering said respective first and second brush heads when not in use, complementary rib and groove means carried jointly by said brush heads and said first and second covering and handle means for mutual frictional engagement to constrain accidental disengaging motion of the covering means from the handle means, said covering and handle means being constructed and arranged so that upon disengagement of either thereof, its underlying brush head is exposed for operative use, while the other brush head remains covered, and its covering and handle means forms a protective handle for the user, said hub means forming an intervening stop and spacer separating the open ends of said handle means when in contact therewith, cross ventilating means formed through each of said covering and handle means for free access of ambient air to its interior to maintain dry and clean the brush heads, and widely opening hook means carried on at least one of said covering and handle means for engagement with a fixed object in supporting relationship therewith, said hook means being constructed and arranged so that when said covering and handle means forms a handle, a finger of the hand of the user may be engaged therein to enhance the secure engagement of the hand with the device.
